UNITED STATES PATENT OFFICE.

THOMAS JEFFERSON LEAGUE, OF CHICAGO, ILLINOIS.

DESIGN FOR A SPINDLE FOR LIGHTING FIXTURES.

Application filed December 3, 1925. Serial No. 15,627. Term of patent 3½ years.

To all whom it may concern:

Be it known that I, THOMAS JEFFERSON LEAGUE, a citizen of the United States, residing at Chicago, in the county of Cook and State of Illinois, have invented a new, original, and ornamental Design for a Spindle for Lighting Fixtures, of which the following is a specification, reference being had to the accompanying drawing, forming part thereof.

The figure is a perspective view of a spindle for lighting fixtures showing my new design.

I claim:

The ornamental design for a spindle for lighting fixtures, as shown.

In testimony whereof I affix my signature at 10 South La Salle Street, Otis Building, Chicago, Illinois.

THOMAS JEFFERSON LEAGUE.
